UNITED STATES PATENT OFFICE

LESLIE A. RUSSELL, OF MILWAUKEE, WISCONSIN, ASSIGNOR TO KOEHRING COMPANY,
OF MILWAUKEE, WISCONSIN, A CORPORATION

WELDED DIPPER STICK CONSTRUCTION

Application filed February 21, 1931. Serial No. 517,595.

In power shovels and similar machines, it is usual to fabricate the dipper stick upon which the shovel is mounted of two identical members of unitary construction, and it is found that in operation, such dipper sticks are open to the objection of frequent breaking under the great twisting strains and wear to which these sticks are subjected when in operation.

The present invention relates to a novel form of such dipper sticks, wherein there are obtained increased rigidity, increased lightness in weight and increased durability, so that the sticks are capable to endure the shocks and strains incident to the actual operation of these sticks.

It has been proposed previously to this invention to employ dipper sticks embodying the use of angles and plates butt-welded together, the welds being along the corners of the dipper stick units, in which constructions the welds must themselves withstand the twisting stresses encountered, which frequently cause the welds to crack and to break open.

In this present construction there is provided a dipper stick comprising two duplicate side members each member formed of opposing pairs of channels welded together along adjoining edges so that this weld will be along the neutral axis of the dipper stick. This results in avoidance of bumping or twisting of the sticks by any internal stresses set up by the welding, and the weld being along the neutral axis, it is submitted to less amounts of external stress, the rigid steel corners taking the load. Each of the side members, therefore, is of hollow construction, but by the provision of suitable reinforcing means, either internally or externally of the hollow space enclosed by the opposing channels, the required rigidity of the dipper stick is effected.

The invention will be readily understood from the accompanying drawings, in which:

Figure 1 is a plan view of a dipper stick constructed in accordance with this invention.

Figure 2 is a side elevation thereof.

Figure 3 is a section along the line 3-3 of Figure 2.

Figure 4 is a section along the line 4-4 of Figure 2.

Figure 5 is a view of a somewhat different form of dipper stick from that illustrated in Figure 1, the figure being a plan.

Figure 6 is a side elevation of the dipper stick of Figure 5.

Figure 7 is a sectional view along the line 7-7 of Figure 6.

Figure 8 is a sectional view along the line 8-8 of Figure 6, and

Figure 9 is a view of a reinforcing member employed in the construction of Figures 5 to 8.

Referring to the drawings, the dipper stick 10 is formed of the duplicate side members 11 and 12, and since these members are duplicates, only a description of the construction of one of them will be required.

The members 11 and 12 carry the dipper stick foot casting 13.

The members 11 and 12 are made up of a pair of angle members 14 and 15, joined together along their corresponding edges. These corresponding edges are beveled as shown at 16 and 17, so that the joints between them are outwardly tapering. The angles 14 and 15 are welded along these joints as indicated at 18 and 19, the weld substantially filling the joints, and because of its configuration, it produces a union of progressively increasing strength.

The dipper stick foot casting 13 is bolted to each side member 12 by bolts, not shown, extending through the bolt holes 20, and there is also provided a plurality of holes 21, 22 and 23 extending through the channel members 14 and 15, there being positioned interiorly of the channel members in engagement with these holes, the plates 24, 25 and 26, which serve as reinforcing plates, and which are welded to the channel members 14 and 15 through the holes 21, 22 and 23 respectively.

As illustrated for additional reinforcement, the plate 25 is shown as extending substantially longer than the upper and lower plates 24 and 26, although this is only a detail of construction.

As will be seen from the drawings (Figure 3) the members 24, 25, and 26 are welded by

angle welds to the continuous inner surface of the channel 14, the said members being welded to the channel 15 through the openings or perforations 21, 22, and 23.

5 To the underside of the channel members 14 and 15 is welded the rack 27, the welds being indicated at 28.

It may be here pointed out that the nature of the welds attaching the reinforcing plates

10 24, 25 and 26 is that of rivet welds, although in Figure 3, it will be seen that the weld extends around the angles between the plates as indicated in black on Figure 3.

15 The member 12 is provided with a cap at its end 28, which extends over the end of the rack 27 to serve as a stop for the rack during racking operations.

20 Angle plate 29 is provided to give a tight fit between the cap 28 and the channel members 14 and 15.

25 In the construction illustrated, in Figures 5 to 9 inclusive, the channel members 14a and 15a making up either of the side members 11a or 12a of the dipper stick 10a, are welded as before described along their adjoining edges as indicated at 17a and 18a, these welds having the outwardly tapering configuration previously described, and being along the neutral axis of the dipper stick. The channel 30 members 14a and 15a are pierced by the aligned holes indicated at 21a and 22a, which holes are for the purpose hereinafter described.

35 It will be seen from the drawings that spaced along the length of the channels 14a and 15a are the reinforcing plates 30 which extend transversely across the space enclosed by the channel members 14a and 15a, these plates being of substantially the configuration 40 of the hollow space between the channel members, substantially filling the cross-sectional area of this space. The plates 30 are welded in position by rivet welds extending through the holes 21a and 22a, these rivet 45 welds being indicated at 31. Thus, these plates are rigidly secured in position.

50 To serve as further reinforcement of the channel members, there may be provided upper and lower plates 32 and 33 respectively, 55 these plates being welded at their edges to the channel members as shown at 34, and may also be further secured in position by means of bolts or rivets 35 extending completely through the plates 32 and 33 and the channel members, thus securing very rigidly together the various parts of the assembly.

55 Welded to the plate 33 is the rack 36, the welds being indicated at 37.

It will be apparent from consideration of

this description that there is thus provided a very rigid construction, none of the welded parts of which is submitted to the strains and shocks incident to the operation of the device. It will be apparent that many changes in the details of the construction may be made without departing from the inventive concept, and it will be understood that it is intended and desired to embrace within the scope of this invention, such modifications and changes as may be required to adapt it to varying conditions and uses.

Having thus described my invention, what I claim as new and desire to secure by Letters Patent of the United States, is:—

1. A dipper stick comprising a pair of side members, each of which is formed of a pair of opposing channel members placed together and welded along their adjoining edges, at least one of the said channel members having spaced apart series of aligned openings therethrough, and a plurality of reinforcing plates within the channel members, the said plates having edge surfaces engaging the inner faces of the channel members and registering with the said openings, and being secured in position by angle welds at the inner surface of one of the channel members and by rivet welds through said openings in the other channel member.

2. A dipper stick comprising a pair of side members each of which is formed of a pair of opposing channel members welded together along their neutral axis, upper and lower reinforcing plates between the channel members and rivet-welded thereto, the reinforcing plates extending longitudinally of the channel members, and a reinforcing plate intermediate the upper and lower plates and also rivet-welded to the channel members, the intermediate plate being substantially longer than the top and bottom plates.

3. A dipper stick comprising a pair of side members each of which is formed of a pair of opposing channel members welded together along adjoining edges, upper and lower reinforcing members extending longitudinally externally along the channel members and welded thereto, a rack member welded to the lower reinforcing member, and spaced reinforcing members extending transversely interiorly of the channel members and rivet welded thereto, each of the transverse reinforcing members having a configuration corresponding to the cross sectional shape of the space enclosed by the channel members.

In testimony whereof I affix my signature.

LESLIE A. RUSSELL.
